(57) **CLAIM**

The ornamental design for a mint dispenser key ring, as shown and described.

DESCRIPTION

FIG. 1 is a front elevation of a mint dispenser key ring, showing my new design;
FIG. 2 is a top plan view thereof;
FIG. 3 is a right elevation thereof;
FIG. 4 is a bottom plan view thereof;
FIG. 5 is a left elevation thereof;
FIG. 6 is an isometric view thereof, showing the dispenser closed; and,
FIG. 7 is an isometric view thereof, showing the dispenser open.
